US00D843669S

(12) **United States Design Patent** (10) **Patent No.:** **US D843,669 S**
(45) **Date of Patent:** **** Mar. 19, 2019**

(54) **FLEA CONTROL APPARATUS**

(71) Applicant: **DaVinci II CSJ, LLC**, Fairfield, NJ (US)

(72) Inventor: **Damian Mucaro**, Hackensack, NJ (US)

(73) Assignee: **DaVinci II CSJ, LLC**, Fairfield, NJ (US)

(**) Term: **15 Years**

(21) Appl. No.: **29/661,644**

(22) Filed: **Aug. 29, 2018**

(51) LOC (11) Cl. **30-99**

(52) U.S. Cl.

USPC **D30/159**; D30/158

(58) **Field of Classification Search**

USPC ..... (57) **CLAIM**

The ornamental design for a flea control apparatus, as shown and described.

DESCRIPTION

FIG. 1 is a perspective view of a flea control apparatus in accordance with the present design;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines and unshaded portions contained within broken line depict unclaimed features of the flea control apparatus that form no part of the claimed design but are shown for purposes of illustration.

1 Claim, 7 Drawing Sheets
